SEATING FOR STADIUMS OR GYMNASIUMS

Birch D. Easterwood, Fort Worth, Tex.

Application October 19, 1945, Serial No. 623,200

2 Claims. (Cl. 20—1.126)

1

This invention relates to seating structures for stadiums and more particularly to prefabricated seats and supporting means.

The principal object of the invention is to provide a ramp or main seat supporting fabrication of structural steel or concrete, on which is superimposed frames of prefabricated construction adapted to support boards or slabs forming seating accommodations and walkways. The arrangement is such that the seat and walk-way frames may be assembled in units at one point for parallel disposition on the inclined sub-structure at another point, thus minimizing the time and labor usually required to install individual seats in a stadium or the like.

Another object of the invention is to provide seat frame assemblies, each consisting of an elongated anchoring plate on which the frames are affixed in spaced relationship as by welding or other means so that the seat and sub-frames will lie on a horizontal plane in relation to the predetermined angular plane of the sub-structure. Moreover, provision is made in each seat and sub-frame for slidably receiving and retaining boards or slabs as seats and walk-ways without requiring nails, bolts or other fastening means.

Still another object of the invention is to provide equipment for washing the sub-structure, in the case of concrete, of refuse left by a crowd, and a gutter for receiving and disposing of such refuse by sluicing the gutter.

With the foregoing objects as paramount, the invention has further reference to certain features of accomplishment which will become apparent as the description proceeds, taken in connection with the accompanying drawing wherein:

Figure 1 is a fragmentary elevational view in vertical section of a seating arrangement for stadiums, constructed according to the present invention in which the sub-structure is of concrete.

Figure 2 is a view similar to Figure 1, but showing in perspective the upper portion of the sub-structure as a continuation of Figure 1.

Figure 3 is a fragmentary elevational view in vertical section, showing a modified form of sub-structure.

Figure 4 is a continuation of Figure 3, showing the upper portion of the seating arrangement and sub-structure, and

Figure 5 is a detail perspective view of a seat and sub-frame, the anchoring plate being shown fragmentarily.

Continuing with a more detailed description of 55 placement although it may be slid longitudinally,

2

the drawing, reference is primarily made to Figures 1 and 2 in which the ramp or sub-structure 10 is constructed of concrete, as are the reinforcing beams 11. The upper surface of the ramp is smooth and without openings of any kind insofar as the seating area thereof is concerned.

At the foot of the ramp 10 there is constructed a gutter 12, also of concrete over which is disposed a grating 13, over which persons may walk in entering and leaving the aisles flanking the seating areas. At the top of the ramp 10 and as exemplified in Figure 2, a horizontal walk-way 14 is provided, at the edge of which is constructed a vertical wall 15.

15 Extending the length of the wall 15 or, in other words, the width of the ramp 10, is a pipe 16 having perforations 17 therein. One end of this pipe is closed and its opposite end is connected to a source of water supply and by suitable valve 20 means, not shown, water may be released into the pipe to emerge through the apertures therein and flow downwardly over the ramp 10, carrying with it all refuse deposited on the ramp by spectators, into the gutter 12 and subsequently disposed of by sluicing the latter.

However, chief among the features of the present invention is the novel seating arrangement, its construction and mode of mounting the same on the ramp 10. The seating arrangement has been and will be hereinafter described as consisting of seat assemblies, each being comprised of an anchoring plate 18 and a plurality of longitudinally spaced seat and sub-frames. The seat and sub-frames each consist of an upright 19, 35 the foot 20 of which is bent into a plane parallel to that of the anchoring plate 18 and to which it is affixed, preferably by welding. The upper portion 21 of the upright is bent at right angles thereto and serves as a support for a board or slab 22, whose edges are longitudinally grooved at a.

An angular brace 23 extends between the upright 19, adjacent its lower end and the forward end of the seat supporting portion 21 thereof 45 and is welded or otherwise secured at both ends; however, the upper extremity of the brace 23 is bent upwardly and inwardly to form a tongue 24 which enters the groove a in the front edge of the board or slab 22, thus retaining it in cooperation with a confronting tongue 25, on a bracket member 26, bolted or otherwise affixed to the upright 19 and extending slightly above the top thereof. By virtue of the retaining tongues 24 and 25, the seat 22 is held against lateral displacement although it may be slid longitudinally,

which is the method employed to install the same in the described frames, which latter are spaced both laterally and longitudinally on the ramp 10.

To provide a walk-way between the seats 22, a sub-frame is provided, consisting of a horizontal support 27, welded to the upright 19 intermediate its ends and extending rearwardly and is bent downwardly and at an angle to define a foot 28 which parallels the anchoring plate 18 and is affixed thereto as by welding. The end of the support 27 next adjacent to the upright 19 is turned outwardly to define a tongue 29 which enters a groove *b* in a board or slab 30 to retain the latter, in cooperation with a confronting tongue 31 on a bracket 32, bolted or otherwise secured to the opposite end of the support 27, as shown in Figure 1. It is obvious that the tongues 29 and 31 hold the board or slab 30 against other than longitudinal displacement as in the case of the seat 22.

From the foregoing, it is readily apparent that the seat assemblies may be conveniently and economically prefabricated at the place of manufacture according to specifications prescribing the construction and angularity of the support on which they are to be permanently mounted, i. e., the ramp 10. Subsequent work of setting up and anchoring the seat assemblies becomes a minor and inexpensive task which may be performed by unskilled labor.

Inasmuch as the structure illustrated in Figures 3 and 4 differs from that just described only in the sub-structure, the same characters of reference are used to indicate like parts except for the said sub-structure, which consists of I-beams 33 or other structural steel forms, serving as the main support and these, in turn, are supported on columns 34 of the same general design. Any accepted practice in bracing the beams 33, such as the braces 35, may be employed to insure adequate support of the sub-structure. It is pointed out, however, that in the latter or modified form of sub-structure, the anchoring plate referred to in the preceding description as 18, is unnecessary in the modified form since the seat and sub-frames may be secured directly to the beams 33, as by welding or otherwise, and the entire assembly, including the beams, may be fabricated at the point of manufacture and subsequently installed at the stadium at the desired angle, thus saving much time and expense otherwise consumed at the point of installation.

Manifestly, the construction as shown and described is capable of some modification, and such modification as may be construed to fall within the scope and meaning of the appended claims is also considered to be within the spirit and intent of the invention.

What is claimed is:

1. A seating arrangement for a stadium and the like including an inclined supporting struc-

ture and a plurality of seat assemblies, each consisting of an inclined and continuous anchoring plate and a series of longitudinally spaced uprights thereon, the latter each having a right angularly disposed and horizontal upper portion, and a foot on its lower portion disposed parallel with and affixed to said anchoring plate, an oblique brace extending between said upright and the forward end of the horizontal portion thereof and whose upper end is disposed to define a tongue above and in a plane parallel with said horizontal portion, a bracket on the opposite end of said horizontal portion having a tongue confronting that of said brace, an elongated seat supported for longitudinal sliding displacement on said horizontal portion, a sub-frame on each of said uprights below the horizontal portion thereof having a return flange on its forward end, a foot on its rear end parallel with and affixed to said anchoring plate, a bracket affixed to the rear end of said sub-frame whose upper end is disposed in parallelism with said sub-frame and in confronting relationship with the return flange thereof to define a tongue and an elongated walk-way having grooved edges slidably received by the return flange of said sub-frame and the tongue of said latter bracket.

2. A seat supporting structure including an inclined sub-structure and a plurality of seat assemblies corresponding to the inclination of said sub-structure, each of said assemblies having individual seat and walk-way supporting frames, the former comprising an upright whose upper portion is disposed in a horizontal plane to define a seat support, an angular bracket extending from said upright to the forward end of said seat support and having a tongue formed thereon above said seat support, a bracket on the opposite end of said seat support, having a tongue confronting said first tongue, a sub-frame on said upright below said seat support having a return flange thereon defining a tongue, a bracket on the rear end of said sub-frame having a tongue in confronting relationship with that of said sub-frame, an elongated seat disposed on said seat support having grooved edges for slidably receiving the tongues on opposite sides of said support and an elongated walk-way supported on said sub-frame having grooved edges for receiving the tongues at each end of the latter.
